(57) **CLAIM**

The ornamental design for a combination turkey call, substantially as shown and described.

DESCRIPTION

FIG. 1 is a side perspective view of a combination turkey call in accordance with an embodiment of the present design;

FIG. 2 is a front elevation view of the turkey call shown in FIG. 1;

FIG. 3 is a back elevation view of the turkey call shown in FIG. 1;

FIG. 4 is a right side elevation view of the turkey call shown in FIG. 1;

FIG. 5 is a top plan view of the turkey call shown in FIG. 1; and,

FIG. 6 is a bottom plan view of the turkey call shown in FIG. 1.

The left side elevation view is not shown because it is a mirror view of the right side elevation view.
